UNITED STATES PATENT OFFICE.

TELESPHORE ALLEMAN, OF CENTREVILLE, LOUISIANA.

PLOW.

SPECIFICATION forming part of Letters Patent No. 279,308, dated June 12, 1883.

Application filed November 16, 1882. (No model.)

To all whom it may concern:

Be it known that I, TELESPHORE ALLEMAN, a resident of the town of Centreville, parish of St. Mary, and State of Louisiana, have invented 5 a certain new and useful Improvement in Plows; and I do hereby declare the following to be a full, clear, and correct description of the same, reference being had to the annexed drawings, making a part of this specification.

10 This invention is intended more especially for "opening up" sugar-cane lands. It is also well adapted for "cutting up" pea-vines and for covering them at the same time, and it may be employed with advantage as a general culti- 15 vator.

My invention consists in the combination, with a plow-beam and rolling colter, of a right and left plow placed at such distance apart as to allow the colter to work in the space between 20 them, as will be hereinafter more fully described.

My invention further consists in the combination of a right and left plow attached to a single beam and placed at a slight distance 25 apart, a rolling colter arranged to run in the space between the plows, and a roller placed centrally in the rear of the plows, as will be hereinafter more fully set forth and specifically claimed.

30 Figure 1 is a side elevation of my improved plow, and Fig. 2 is a plan or top view thereof. Fig. 3 is a top view of the plows and rolling colter detached from the beam, so as to show more fully the relative positions of each.

35 The letter A designates the beam, B the clevis, and C the handles, all of which are of the ordinary construction, with the exception, perhaps, of the beam being made a little wider than ordinarily, especially at that part to 40 which the plows are connected. The plow-standards d and slides e, at the rear of the same, are secured by means of bolts f g, so as to leave a space between the plows, within the forward part of which is suspended, from an adjustable

frame, H, a revolving disk or colter, I, the 45 axle of which is journaled in the aforesaid frame, as shown at i. In rear of the plows the beam is provided with a second adjustable frame, K, within the lower extremities of which is journaled a roller, l, for pulverizing the clods 50 of earth which may fall into the trench or furrow left by the plows. The rear portion of the latter frame, K, has pivoted therein a scraper, m, the lower end or point of which serves to remove from the roller any earth 55 which may adhere to the same. The frames H and K are secured to the beam by means of bolts o o', and are each provided with a slotted end, as shown at p p', in order that they may be properly adjusted and secured at such height 60 as will provide for the operating parts, mounted therein, to perform their functions more effectually.

This plow is well adapted for opening cane-lands, as well as for cutting up pea-vines and 65 covering them at the same time.

Having described my invention, what I claim as new, and desire to secure by Letters Patent, is—

1. In an opening-plow, the combination, with 70 a single beam and a rolling colter, of a right and left plow placed side by side and at such distance apart as to allow the colter to work in the space between them, substantially as shown and described.

2. In an opening-plow, the combination of the right and left plows attached to a single beam and placed at a slight distance apart, the rolling colter arranged to run in the space between the plows, and a roller placed centrally in the rear of the plows, substantially as shown and described. 80

In testimony whereof I affix my signature in presence of two witnesses.

TELESPHORE ALLEMAN.
